(57) **CLAIM**

The ornamental design for a contact lens inserter, as shown and described.

DESCRIPTION

FIG. 1 is a top right front perspective view of a contact lens inserter showing my new design;

FIG. 2 is a bottom right front perspective view thereof;

FIG. 3 is a front view thereof;

FIG. 4 is a top plan view thereof;

FIG. 5 is a left side elevational thereof;

FIG. 6 is a right side elevational view thereof;

FIG. 7 is a back elevational view thereof; and,

FIG. 8 is a bottom plan view thereof.

The broken lines shown in the drawing Figures are included for the purpose of illustrating portions of the contact lens inserter that form no part of the claimed design.

“DMV” shown in broken lines and forming no part of the claimed design is a registered trademark of D M V Corporation CORPORATION OHIO P.O. Box 8781024 Military Rd. Zanesville OHIO 43701.

1 Claim, 4 Drawing Sheets
